CROSS-BAR SWITCH FOR USE IN AUTOMATIC TELEPHONE SYSTEMS

Gunnar Börge Knös, Eindhoven, Netherlands, assignor to Hartford National Bank and Trust Company, Hartford, Conn., as trustee

Application February 12, 1949, Serial No. 76,158
In the Netherlands March 15, 1948

4 Claims. (Cl. 179—27.54)

1

The instant application is a continuation-in-part of the copending application by the same inventor filed on December 6, 1947, and given Serial Number 790,085.

The invention relates to improvements in or modifications of the invention described and claimed in said copending application. In this copending application is described a cross-bar switch of the kind comprising contact wires for automatic telephone systems and the movable contact bodies of which are constituted by metal wires bent in a labyrinthine manner (movable contact wires) and crossing all the stationary contact wires of a grid opposite the contact areas. These movable contact wires exhibit a number of bows (contact bows) located in the same plane and engaging linking members and are supported between them by stationary supports. On a linking member being moved across the plane of the contact bows, the tips of the contact bows bearing on these linking members are moved and engage the stationary contact wires with which they co-operate.

The cross-bar switch according to the above-identified copending application may be constructed so that the linking members must exercise a force on the contact bows to bring them into engagement with the stationary contact wires. As an alternative, the movable contact wires may be given already in their position of rest a mechanical stress which tends to move the contact bows towards the stationary contact wires. In this case the linking members must exercise a force on the contact bows to keep them clear of the stationary contact wires. In order that this stress may be obtained the pieces of the wire which link the contact bows to one another must be fixed on the stationary supports.

This is required even in the first case in order to prevent the force exercised by a linking member on a contact bow from being transferred by way of the adjacent contact bows to the linking members co-operating therewith and from shifting said linking members or warping the contact bows.

It has been suggested in the above-identified copending application to provide the movable contact wires not only with contact bows but also with secondary bows by means of which they are secured to the stationary supports. Since they serve to stress the movable contact wires they are referred to as stressing bows. But for these stressing bows, to secure the movable contact wires would require a great clamping force. The stressing bows furnish a lever arm for the reactive force, which is thus enabled to be materially reduced.

In the embodiments shown in the drawing accompanying the above-identified copending application the contact bows exhibit a shape bent outwardly over the stressing bow. This permits of the stationary contact wires of two adjacent

2

channels being brought into closer proximity and of the dimensions of the assembly being thus reduced.

It has furthermore been pointed out already in the above-identified copending application that it is possible for the stressing bows tightly to embrace the supports. Although not being indispensable, it has the advantage that the linking members are subject to forces in their own direction only and need not also act to prevent the stressing bows from slipping out of the notches in the supports. Upon a contact wire constructed in this manner being positioned, the insertion of a support in a stressing bow has the effect of spacing the arms of this bow further apart and then causing them to slide pinchingly on either side along the support till the inwardly bent feet of the stressing bow have reached the end of the support and snap around it resiliently. In this case more or less rough handling may damage the wires of the supports and this is avoided by the use of the invention.

It relates to an improvement in a cross-bar switch according to the above-identified copending application in which the movable contact wires are provided with stressing bows. In the cross-bar switch according to the invention the contact bows supply a force which holds the stressing bows in place on the supports. This force is produced in that in the contact bows is available a bending stress which tends to force apart the feet of these bows. When providing a movable contact wire on a support, the arms of the contact bow require to be clamped but there is no need for the stressing bow to be bent open to any appreciable extent. This permits of the stressing bows being put on the supports without any appreciable friction. Not until it has been positioned, is a stressing bow fixed in position by causing the next following to surround support.

The arms of the contact bows shown in the drawing accompanying the above-identified copending application are parallel and they are interconnected at the end by an eyelet. For clamped contact bows this form is less suitable, since it requires that prior to the stressing operation the tips of the contact bows should not be located on a straight line but instead on a circle or helix, which renders manufacture more difficult. With a cross-bar switch according to the invention, it is of advantage to shape the stressed contact bows into the form of an isosceles triangle the apex of which lies at the feet of the bow, or into the form of a spatula. If the bow height is the same, the required deformation is smaller and the bow is less rigid. In addition, the wires are stressed more readily.

In order that the invention may be more clearly understood and readily carried into effect, it will now be described with reference to the accompanying drawing, in which

Fig. 1 shows, on an enlarged scale, by way of

example, part of a movable contact wire of a cross-bar switch according to the invention, viewed in the direction of movement of the linking member.

Fig. 2 is a sectional view taken on the line 5 II-II.

Fig. 3 is a sectional view taken on the line 10 III-III.

Fig. 4 shows the shape of the same wire before 15 being stressed.

Fig. 5 shows an alternative form of the contact bows.

As may be seen from Fig. 1, the contact bows, apart from small curvatures due to the stressing operation, are shaped into the form of an isosceles triangle, the apex of which lies at the feet of the bows. The contact piece 1 which extends along the base of this triangle bears on the wall 2 of a notch in the linking member 3. The contact bows are separated by stressing bows 4, which bear on the wall 5 of a notch in combs 6. These combs 6 connect strips 7 which leave gaps 8 in which are located pieces 9 of the wire which connect the stressing bows to the contact bows. Linking members, combs and strips are 20 made of insulating material.

Assuming the projection plane of Fig. 1 to be horizontal and that of Fig. 2 to be vertical, the movable contact wires may be said to be stretched in a vertical direction between the combs and the linking members. The contact bows urge 25 downwardly against the linking member and the stressing bows upwardly against the comb. When a linking member is being moved downwards, the contact pieces 1 come down on the 30 stationary contact wires 10. The wall 2 of the notch in the linking member is thus separated from the contact bow and the latter is caused to bear on the wires 10 with a contact pressure 35 which is supplied by the resilient force of the 40 movable contact wires.

According to the invention, the movable contact wires have a tension also in a horizontal direction, this tension being directed so as to tend to separate the arms 11 of the contact bows. 45 Prior to the stressing operation, the wires are in appearance as shown in Fig. 4, the contact bows having a rectangular form into which they are more readily shaped with the use of simple tools than into a form in which the contact pieces extend beyond the feet of the bows. By putting the wire on the combs 6, the arms 11 are urged towards one another and the triangular shape into which the contact bows of Fig. 1 are formed is produced. The pieces 9 are urged against the 50 combs 6 by the resilient force of the contact bows with the result that the feet 12 of the stressing bows clasp the combs. The wire is thus prevented snapping from the combs and need not be held by the linking member.

Prior to the stressing operation the feet 12 of the stressing bows are spaced apart to such an extent that the combs fit between them. In Fig. 4 one of the combs 6 is shown in broken lines to illustrate this. Consequently there is no need for the wire to be slipped forcibly over the combs but may be put on it without any appreciable friction.

The stationary contact wires 10 are arranged in pairs. Each contact bow co-operates with 70 two stationary contact wires of the same pair. The linking members are invariably arranged between the wires of each pair. They are provided with key-shaped extensions 13 which serve to urge the stationary contact wires, after the 75

contact bows have been brought into engagement therewith, slightly apart during the further movement of the linking member. The wires are thus caused to slide over the contact pieces 1 and the points of contact are cleaned by friction.

What I claim is:

1. In a cross-bar switch for automatic telephony provided with a planar grid constituted by a group of paired linear conductors disposed in spaced relation and serving as the passive contacts of said switch, an active contact structure comprising a plurality of resilient wires disposed in spaced positions transversely with respect to said conductors, each wire being flexibly shaped to form alternate active contact bows and stressing bows, each of said active bows intersecting a respective pair of conductors, and a supporting comb for each of said stressing bows, successive combs for the stressing bows having a spacing therebetween which is smaller than the spacing between the corresponding stressing bows of the wire before they are attached to the combs, each of said contact bows having a pair of side arms which when urged together and then released when said stressing bows are received by said combs impart a resilient force against the adjacent stressing bows to cause said stressing bows securely to clasp their associated comb.

2. An arrangement, as set forth in claim 1, wherein the shape of each contact bow is such that when the arms are urged together the contact bow assumes substantially the shape of an isosceles triangle.

3. An arrangement, as set forth in claim 1, wherein the shape of each contact bow is such that when the arms are urged together the contact bow assumes substantially a spatulate contour.

4. In a cross-bar switch for automatic telephony provided with a planar grid constituted by a group of paired linear conductors disposed in spaced relation and serving as the passive contacts of said switch, an active contact structure comprising a plurality of resilient wires disposed in spaced positions transversely with respect to said conductors, each wire being flexibly shaped to form alternate active contact bows and stressing bows, each of said active bows intersecting a respective pair of conductors, and a supporting comb for each of said stressing bows, successive combs for the stressing bows having a spacing therebetween which is smaller than the spacing between the corresponding stressing bows of the wire before they are attached to the combs, each of said contact bows having a generally rectangular configuration defined by a pair of parallel side arms interconnected at the ends by a cross arm, whereby when said side arms are urged together and then released when said stressing bows are received by said combs, they impart a resilient force against the adjacent stressing bows to cause said stressing bows securely to clasp their associated combs.
